UNITED STATES PATENT OFFICE

HAROLD EDGAR YARROW, OF SCOTSTOUN, SCOTLAND

WATER TUBE BOILER OF THE YARROW TYPE

Application filed March 28, 1929, Serial No. 350,647, and in Great Britain April 4, 1928.

This invention relates to water tube boilers of the Yarrow type having two elevated steam drums and consists in an improved construction of such boilers which has for its principal object to provide a boiler of large capacity, while retaining the advantages, inherent in the Yarrow type of boiler, which results from the provision of nests of steam generating tubes at each side of the furnace.

It has been proposed in water tube boilers having two steam drums each connected with a parallel water drum on the same side of the furnace by an inclined bank of water tubes, transversely traversed by the furnace gases on their way to the uptake, to provide cross-connecting tubes adjacent to the combustion space between each water drum and the steam drum on the opposite side of the furnace to balance the pressure in the said steam drums.

According to the present invention these cross-connecting tubes between the two water drums (or between the two innermost water drums when there is more than one water drum on each side of the furnace) and the two steam drums have a pitch in the longitudinal direction of the steam and water drums very considerably greater than the pitch of the other steam generating tubes connecting the water drums with the steam drums, thereby precluding "birdnesting", while still effectively screening the parts of the steam drums which would otherwise be exposed to direct radiation from the furnace. Moreover, as the cross-connecting tubes keep the spaces behind them relatively cool, "birdnesting" is also prevented in the inclined banks of steam generating tubes in rear of the cross-connecting tubes.

The invention is illustrated in the accompanying drawings, wherein Fig. 1 shows in cross section the parts of a Yarrow type of boiler essential to the understanding of the invention, Fig. 2 is a cross section on line 2-2 of Fig. 1, and Fig. 3 is a view similar to Fig. 1 showing a modification. It is to be understood that any system of firing may be used.

As therein shown, there are provided two steam drums A, A' the steam spaces of which are connected by cross tubes B and the water

spaces by cross tubes C. On each side of the boiler furnace there are two water drums D, E and D', E' respectively, and these water drums are connected with the steam drum on the respective sides by means of nests of generating tubes F, G and F', G' respectively. As shown in the drawings, the nests of tubes F, F' are of considerably greater depth than the nests G, G', and the water drums D, D' are of correspondingly greater diameter.

Further, the water drum E is cross-connected with the steam drum A' by one or more rows of tubes H and similarly the water drum E' is cross-connected with the steam drum A by one or more rows of tubes H'. These tubes may be straight, as shown in full lines in the drawings, or they may be curved as shown in Fig. 3, the latter arrangement being preferred, so as to secure as large a combustion chamber as possible.

In Yarrow boilers the tubes are usually pitched as closely together as possible consistent with ensuring adequate strength of the steam and water drums. Thus, in the boiler illustrated the tubes F, F', G, G' are closely pitched in the usual manner, but the tubes H, H' are widely pitched in the longitudinal direction of the drums E, E', as shown in Fig. 2, with the special object of preventing what is known as bird-nesting, that is to say such an accumulation of a deposit of slag, ash or soot on the tubes as to bridge across the space between adjacent tubes in a row. For this reason the pitch of the tubes H, H' in the longitudinal direction is made twice that, for example, of the tubes G, G'. As, however, the two sets of tubes H, H' interlace with each other in crossing, the parts of the steam drums A, A' which would otherwise be exposed to direct radiation, are still effectively screened therefrom. Furthermore, as the tubes H, H' keep the spaces behind them relatively cool there is for this reason less liability of bird-nesting to occur between the tubes such as G, G' in rear of tubes H, H'.

Between the two nests of tubes F, G and also between the tubes F', G' there may be interposed a superheater or re-heater of any

convenient construction. These are indicated at I and I' respectively.

The furnace gases divide towards the right and left, passing amongst the several groups of tubes on either side and around the outsides of the steam drums to the uptake.

Having thus described the nature of the said invention and the best means I know of carrying the same into practical effect, I claim:

A water tube boiler of the Yarrow type, comprising two parallel steam drums and a plurality of water drums on each side of the furnace and parallel with the said steam drums, inclined banks of steam generating tubes connecting the water drums at each side of the furnace with the steam drum on that side and a plurality of rows of steam generating tubes on both sides of and immediately adjacent to the combustion space and directly connecting the innermost water drum on each side of the furnace with the steam drum on the opposite side of the furnace, the tubes of each row of said plurality of rows of steam generating tubes registering, respectively, with tubes of the adjacent row transversely of said steam and water drums and being spaced apart longitudinally of said steam and water drums approximately twice the distance between adjacent tubes of said banks of steam generating tubes to preclude "bird-nesting", while still effectively screening the parts of the steam drums which would otherwise be exposed to direct radiation from the furnace as well as balancing the pressure in the said steam drums.

In testimony whereof I have signed my name to this specification.

HAROLD E. YARROW.
